UNITED STATES PATENT OFFICE.

JAMES S. KERN, OF PHILADELPHIA, PENNSYLVANIA, ASSIGNOR TO JAMES L. BRANSON, OF SAME PLACE.

CIRCULAR-KNITTING MACHINE.

SPECIFICATION forming part of Letters Patent No. 432,051, dated July 15, 1890.

Application filed January 21, 1889. Serial No. 296,982. (No model.)

To all whom it may concern:

Be it known that I, JAMES S. KERN, a citizen of the United States, residing at the city and county of Philadelphia and State of Pennsylvania, have invented certain new and useful Improvements in Circular-Knitting Machines, of which the following is a full, clear, and exact description, reference being had to the accompanying drawings, of which—

10 Figure 1 is an elevation on a flat plane of the cams of a knitting-machine in which my invention is embodied, the rotatable supporting-cylinder being represented in dotted outline. Fig. 2 is a plan view of a portion of 15 the cam-cylinder with my invention applied thereto. Figs. 3 and 4 are end and front views, respectively, of the guard-cam and its connections as detached from the machine. Fig. 20 5 is an illustrative view of the operation of the guard-cam. Fig. 6 is a detail of stop device.

The nature of this invention is a device which I term a "guard-cam," for preventing the end of the upper cam of a circular-knitting machine from striking against a needle or needles and consequently breaking the latter or the needle-cylinder, or both, in case said needle or needles should happen, by accident or otherwise, to be above the mouth of the 25 cam-groove during the operation of the machine—as, for instance, upon failure of the operator to properly depress or raise the needles while knitting the heel and toe parts of a stocking or other hosiery.

30 The invention consists in a novel construction and arrangement of the guard-cam and in certain details, which will be hereinafter fully described and duly claimed.

In the annexed drawings, A is the rotatable 35 cam-cylinder, B its cams, and C the needle-rest. These parts are constructed and operate in the same manner as the like parts in the well-known "Branson" knitting-machine, which is shown and described in various Letters Patent of the United States, among others in No. 214,989, dated May 6, 1879.

D is the guard-cam. It is triangular in form, and is secured at one of its corners d' to a pivot pin or shaft d^2 , which projects

through the side of the cam-cylinder adjacent 50 to and below the end of the upper cam b' , as shown. This shaft, which is mounted in a bed-plate d^3 , that is screwed or otherwise firmly secured to the exterior of cylinder A, has formed or attached to its outer end a 55 head or collar d^4 , between which and the plate d^3 is interposed a spring d^5 , preferably spiral. The ends of this spring are inserted within, or in some other suitable manner rigidly connected with, the plate d^3 and collar d^4 , respectively, so that the torsional action of the spring will normally throw the guard-cam away 60 from the end of cam b' . Extending from the shaft d^2 , or rather from its collar d^4 , is an arm d^6 , which, in conjunction with a projecting 65 stud or pin d^7 , against which it abuts, limits the movement of the cam and prevents its forward nose or corner d^8 from being turned below the pivotal point d' .

Having thus described the construction of 70 the device, I shall now explain its *modus operandi*, which is as follows: As the cam-cylinder is being rapidly rotated in the direction of the arrow marked 1, if the heel h , Fig. 5, of a needle happen, by accident or otherwise, to 75 be above the mouth of the cam-groove x , one of the inclined edges of the cam D or its nose d^8 will strike heel, and accordingly direct the latter above or below the end of the upper cam without damage to the needle or 80 the machine. If the nose d^8 of the cam come into contact with the heel of the needle, it (said nose) will be forced back against the action of the spring d^5 , and thus guide the 85 heel of the needle to the inclined upper end of the cam b' , as indicated by the dotted lines in Fig. 5. Should the needle-heel strike the upper edge of the guard-cam the needle will be deflected upward and above the end of cam b' ; and, on the other hand, if said heel shall strike the lower edge of the guard-cam the needle will be directed thereby to the mouth of the cam-groove x .

A guard-cam similar in construction to the one above described, and operating in a like 95 manner and for a like purpose, is pivoted with respect to the other end of cam b' , said duplicate cam being brought into action when

the motion of the cam-cylinder is reversed during the operation of knitting the heel or toe parts of a stocking, &c.

I sometimes provide the collar d^4 on the end 5 of the pivot-shaft of the guard-cam with a projection e , Fig. 6, which will abut against the pin d^7 , and thus check the movement of said cam when the nose of the latter has been turned by the needle or needles to the end of 10 the upper cam. By this construction, should the spring become broken or too weak to return the cam to its normal position, the nose of said cam will be prevented from dropping down below the upper cam and interfering 15 with the needles.

I claim as new and wish to secure by Letters Patent—

1. In a knitting-machine, the combination, 20 with the cam-cylinder, of the guard-cam pivoted in the side of said cylinder at a point adjacent to and below the end of the upper cam, so that when the forward point or nose of said cam engages with a needle the cam will swing or turn until said forward point or 25 nose is carried to or near to said end, thereby permitting the needle to pass onto the upper surface of the upper cam, substantially as described, the outwardly-extending pivot pin or shaft, and means, such as the spring, connected with said shaft and operating to normally hold the nose of the guard-cam away 30 from the end of the upper cam, substantially as and for the purpose set forth.

2. In a knitting-machine, the combination, 35 with the cam-cylinder, of the guard-cam pivoted in the side of said cylinder at a point adjacent to and below the end of the upper cam, so that when the forward point or nose of said cam engages with a needle the cam

will swing or turn until said forward point or 40 nose is carried to or near to said end, thereby permitting the needle to pass onto the upper surface of the upper cam, substantially as described, the outwardly-extending pivot pin or shaft, and means, such as the spring, connected with said shaft and operating to normally hold the nose of the guard-cam away 45 from the end of the upper cam, together with the stop device for limiting the backward movement of said guard-cam, substantially 50 as and for the purpose set forth.

3. The combination, with a knitting-machine-cam cylinder, of the guard-cam pivoted in the side of said cylinder at a point below and adjacent to the end of the upper cam, 55 the outwardly-extending pivot pin or shaft, the arm d^6 , connected therewith, the fixed stud disposed in the path of said arm, and the spring, all combined, constructed, and adapted to operate substantially as and for 60 the purpose set forth.

4. The combination of the plate d^3 , the pivot-pin d^2 , the triangular cam D on one end thereof, the head or collar d^4 on its opposite end, the spring d^5 , interposed between and rigidly 65 connected with said plate and head, the arm d^6 , extending from the latter, and the stud d^7 , extending from the plate in the path of said arm, all substantially as and for the purpose specified.

In testimony whereof I have hereunto affixed my signature this 22d day of December, A. D. 1888.

JAMES S. KERN.
